BUILDING CONSTRUCTION

Seward Charles, Washington, D. C.

Application November 23, 1934, Serial No. 754,533

2 Claims. (Cl. 189—1)

This invention relates to building construction and more particularly to the relationship between vertical and horizontal framing members, and the conduits for piping, cables and ventilating air currents, providing a construction simple in structural elements and less costly to fabricate than those heretofore proposed.

With these and other objects in view the invention resides in the novel details of construction and combinations of parts more fully disclosed hereinafter and particularly pointed out in the claims.

Referring to the accompanying drawing forming a part of this specification and in which like numerals designate like parts in all the views—

Fig. 1 is a perspective view partly in section of one form of the invention;

Fig. 2 is a sectional view of the parts disclosed in Fig. 1, taken as on the broken line 2—2 thereof and looking in the direction of the arrows;

Fig. 3 is a view somewhat similar to Fig. 1 showing a modified form of the invention;

Fig. 4 is a horizontal sectional view of the construction shown in Fig. 3; and

Fig. 5 is a vertical sectional view taken substantially on the line 5—5 of Fig. 3 and looking in the direction of the arrows.

The vertical framing consists of a plurality of columns, each column comprising a pair of structural channel members such as 2 and 3 having their webs 4 parallelly disposed to each other but spaced as at 6 to accommodate a portion 7 of the web of a horizontal beam 8 preferably of I cross-section.

The beam may be of such a length that it is continuous in the way of a vertical column, or it may be intercostal as shown in Fig. 1. In the latter case the portion 7 of the web will extend substantially half way through the space 6 from one side of the vertical channels, and a corresponding portion 9 of the web of a similar horizontal beam 10 will similarly extend from the other side of said channels into the space 6. Thus it will be understood that the pair of horizontal beams 8 and 10 will be in prolongation of each other and separated by a vertical column such as formed by the channels 2 and 3.

In this respect it is an important feature of this invention that the flanges of said beams are cut away to such a distance from the extreme end of the web portions as not only to accommodate the channels 2 and 3 with said web portions sandwiched between said channels, but to provide a space between the surface of the flanges of each vertical channel and the flanges of the

horizontal beams when said members are assembled, which space is sufficient to accommodate the walls of a duct generally indicated by the numeral 12 as shown. The web portions 7 and 9 of the beams 8 and 10 are suitably secured to the web portions of the vertical channels 2 and 3 as by the rivets 13.

Each duct is formed by attaching to the vertical channels a sheet of relatively thin metal bent into U shape, with the free ends of the U secured to the surfaces of said flanges, whereby it will be seen that the web of a vertical channel will form the fourth wall of said duct. In such securement a coating of paint, plastic material, or other suitable sealing medium is applied between the opposite side walls of the duct and the flanges of a vertical channel to which said walls are riveted or bolted, so that it may be possible to utilize such a duct as a conduit for ventilating air currents.

A sheet metal flooring 14 is bolted on the upper surfaces of the flanges of the horizontal beams such as 8 and 10, said flooring being suitably apertured to accommodate therethrough the ducts above described and of which there may be a single duct 12 or a pair of ducts 12 and 15 at a vertical column, the duct 15 being similarly disposed and secured to the channel 2 as was the duct 12 with respect to the channel 3.

The spacings between the vertical columns and the spacings between the horizontal beams may be made as desired wherefore it may be necessary to provide connections between one horizontal beam and the next adjacent beam in the nature of angle bars such as 16 and 17, particularly to form additional support for the span of the metallic floor plate 14. In such case the surface of the horizontal flange of each angle bar and the top surface of the flange of the horizontal beams will be made to lie in a common plane. The angle bars may be secured to the beams by cutting away the horizontal flange of each bar in the way of the flange of the beam and extending the vertical flange of the bar under the beam flange so that an angle iron such as 18 may be employed to rivet the bars and the beams together. Similar angle bars 19 and 20 may be provided for support of the floor plate 14 in positions closely adjacent the ducts 12 and 15.

The modification shown in Fig. 3 illustrates the construction employed when concrete floors and concrete supporting beams are utilized. Here reinforced concrete is laid to form the floor 24 integrally supported by a plurality of concrete hori-

horizontal beams such as 25 the latter taking the place of the horizontal structural beam such as 8 described above. The vertical channels 26 and 27, similar to the channels 2 and 3, are employed but their webs are spaced apart a greater distance necessitated by the increased width of the concrete beam 25, sleeved spacing bolts 28 securing the vertical channels in proper relation. A suitable structural bracket 29 is riveted or bolted to the channels 26 and 27 for supporting the weight of the horizontal concrete beams, said bracket being disposed entirely between said channels, or exteriorly placed as shown in Fig. 5. The ducts 12 and 15 may be completely formed prior to the pouring of the concrete, or the pouring forms may be so planned as to provide the space for said ducts in which case the U-shaped preformed metallic sheets may be slid vertically through the floor section openings therefor. If desired, the webs of the channels 26 and 27 may be provided with spaced openings in the way of the concrete floor sections to permit the wet concrete when poured to enter said openings and form keys as indicated at 31.

It is obvious that those skilled in the art may vary the details of construction, as well as the arrangement of parts constituting the apparatus without departing from the scope of the invention, and therefore it is not desired to be limited to the foregoing disclosure except as may be demanded by the claims.

What is claimed is:

1. In building construction the combination of a vertical supporting column comprising a pair of spaced structural members provided with web and flange portions, the web portion of one member parallelly facing the web portion of the other; a horizontal beam comprising web and flange portions, the flange portions cut away to accommodate said members, and the web portion disposed in the space between and secured to the web portions of said members; and a duct formed of material having a substantially U-shape, the free edge portions of the material fitting between the ends of the beam flanges and the flanges of one of said members and secured to the latter, the web of said member forming one wall of said duct.

2. In building construction the combination of a vertical supporting column comprising a pair of spaced structural members provided with web and flange portions, the web portion of one member parallelly facing the web portion of the other; a horizontal beam having a portion thereof disposed between and supported by the members of said column; and a duct formed of material having a substantially U-shape, the free edge portions of the material secured to the flanges of one of said members and substantially abutting said beam, the web of said member forming one wall of said duct.

SEWARD CHARLES.
